UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR CONVERTING HYDROCARBONS

Application filed June 6, 1921, Serial No. 475,242. Renewed February 21, 1929.

This invention relates to improvements in apparatus for converting hydrocarbons and refers more particularly to an apparatus for converting relatively high boiling point oils to oils of lower boiling point having the characteristics of gasoline and the like.

Among the salient objects of the invention are to provide an apparatus in which the raw oil treated may be combined with regulated quantities of reflux and residuum and the mixture charged to the heating zone to be raised to a conversion temperature; to provide an apparatus in which the vaporized portions of the oil from the expansion chamber are dephlegmated and condensed, the reflux condensate from the dephlegmating zone being collected as is the residuum or unvaporized portion from the expansion chamber in separate tanks; to provide an apparatus in which regulated quantities of the raw oil, reflux and residuum may be withdrawn from these separate reservoirs or tanks and introduced to the charging line or any desired combination of these oils may be charged to the heating zone as desired.

The single figure is a diagrammatic side elevational view of the apparatus.

Referring in detail to the drawing, the oil to be treated is introduced through the charging line 1 controlled by a valve 2 into the pump 3 which forces the oil into a raw oil reservoir 4. A drawoff line 5 controlled by a valve 6 from this tank or reservoir connects with the inlet line 7 to the heating tubes 8 mounted in the furnace 9. The oil, after being heated to a cracking temperature passes to the expansion chamber 10 to which are connected the vapor line 11 controlled by valve 12 and the residuum line 13 regulated by a valve 14, the latter directing the residuum to a tank 15. The residuum collected in the tank 15 may be withdrawn through the line 16 regulated by a valve 17 and passed to separate storage tanks or it may be withdrawn through the line 18 controlled by a valve 19 and regulated quantities directed back into the inlet line 7 to be retreated with the raw oil in the heating tubes. The vapors passing from the expansion chamber 10 through the vapor line 11 are refluxed in the

dephlegmator 20 from which they pass over to the line 21 to the water condenser 22 and thence to a receiver 23 where they may be drawn from the system through the valve 24. Pressure relief valve 25 and pressure gauge 26 are fitted to the receiver. The reflux oil from the dephlegmator passes down through the line 27 controlled by a valve 28 into the reflux tank 29 where it is collected and may be drawn off to separate storage tanks 4 and 15. It is obvious that by collecting the raw oil, reflux and residuum in separate storage tanks of the type shown, and that by drawing off regulated quantities from time to time, and reintroducing quantities of these different types of oil to the inlet line, an oil charge of the desired character for treatment may be charged to the heating zone. At times during the cracking of the oil, it is desirable to introduce a higher boiling reflux oil or even portions of the residuum products to the raw oil, both for their preheating qualities and also other characteristics of these higher boiling point oils tend to give a higher quality yield of distillate in the receiver.

I claim as my invention:

1. In an apparatus for converting hydrocarbon oils, the combination with means for heating and vaporizing the oil, of dephlegmating and condensing means connected thereto, means for collecting separately the reflux condensate from the dephlegmating means and the residual products from the vaporizing means and means, comprising valves for controlling the outlets from the collecting means for the reflux condensate and the residual products, for introducing said reflux and residual products in regulated quantities with the oil to be treated to the heating means.

2. In an apparatus for converting hydrocarbon oils, the combination with means for raising the oil to a cracking temperature comprising a heating coil, of a vaporizing

chamber connected thereto, dephlegmating and condensing means connected with the vaporizing chamber, means for collecting separately the residual oil from the vaporizing chamber and the reflux condensate from the dephlegmating means, and alternate drawoff lines from said collecting means for directing the residuum and reflux back to the heating means or for directing said products to storage.
